FILE FASTENER

William Lang, West Orange, N. J., assignor to
 The Bates Manufacturing Company, West Orange, N. J., a corporation of New Jersey

Application May 23, 1936, Serial No. 81,448

8 Claims. (Cl. 129—25)

My invention relates to file fasteners, especially those of the type used for binding and securing together perforated and superimposed sheets of paper such, for example, as those which make up ordinary correspondence files.

A common form of this type of file fastener comprises an elongated base or clamping member having bendable tongues or prongs at or adjacent its ends and an elongated keeper or compressor plate over and down against which the free end portions of said tongues, after the latter have been inserted through the sheets to be secured together, are designed to be bent thereby to hold the keeper and clamping member in operative clamping relation with respect to said sheets. In using such a fastener, the compressor plate or keeper is sometimes dispensed with, in which case the end portion of the tongues of the base or clamping member, after insertion of said tongues through the sheets to be secured, are bent down directly against the uppermost of such sheets. While my invention is applicable to various forms of fasteners, the same is especially designed for application to fasteners of the general construction just described.

The principal object of my invention is to provide an improved construction and arrangement whereby the capacity of a file fastener of the character described may readily be increased.

Another object of my invention is to provide a construction whereby the capacity of such a file fastener may be readily increased a plurality of times and to any desired extent.

A further object of my invention is to provide means whereby the capacity of such a file fastener may be increased at any time without disturbing or removing any of the sheets then held by the fastener.

A still further object is to provide a simple and novel form of adapter or extension device capable of being quickly and readily applied to the flexible or bendable tongues of file fasteners of the character above described to increase the effective length of such tongues and thereby the capacity of the fasteners.

Other objects and advantages of my invention will be hereinafter more specifically described, and the novel features thereof will be set forth in the appended claims.

For a better understanding of my invention, attention is directed to the drawing which accompanies and forms part of this specification and in which:

Figure 1 is a view in elevation partly in section and partly broken away, showing a file fas-

tener as used in securing together superimposed sheets of a file substantially to the full normal capacity thereof;

Figure 2 is a view similar to Figure 1 with the compressor plate or keeper of the file fastener omitted, illustrating the application of my improved adapters or extension devices to the tongues of the base or clamping member of the fastener;

Figure 3 is a view similar to Figure 1 showing a file fastener the capacity of which has been increased by the application of an adapter to each tongue of the clamping member, as used in securing together sheets of a file substantially to the limit of its increased capacity;

Figure 4 is a sectional view taken on line 4—4 of Figure 2, with the superimposed file sheets omitted; and

Figure 5 is a view similar to Figure 4, taken on line 5—5 of Figure 3.

In the several views of the drawing, like parts are designated by the same reference characters.

A common form of file fastener is shown in Figure 1, such fastener preferably being formed of thin sheet metal and comprising a clamping member having a substantially rectangular base portion 1 and flexible or bendable flat tongues or prongs 2, and a substantially rectangular keeper or compressor plate 3. The tongues 2 of the clamping member are shown as integrally joined to the base portion 1 at its ends, and in the use of the fastener said tongues are bent so as to project from the base portion at right angles thereto in spaced parallel relation and extended through similarly spaced openings 4 and 5 respectively provided in the superimposed file sheets 6 to be secured together and in the keeper 3 overlying and bearing against the uppermost of said sheets, and the upper projecting end portions 2' are then bent down against the keeper, as shown at the left in Figure 1. If the use of the keeper 3 is dispensed with, the end portions 2' of the tongues may be bent down in either direction against the uppermost of the sheets 6 to thereby hold such sheets together.

In Figure 1, the fastener is shown as securing together superimposed sheets substantially to its full normal capacity. In order to increase the capacity of such a fastener to any desired extent over the normal capacity thereof, I have provided a simple but novel form of adapter or extension device one or more of which may be supported by each of the tongues of the fastener clamping member to increase the effective length of said tongues and which may be readily applied

in operative position to the fastener without removing or disturbing any of the sheets of the file then held by the fastener. A preferred form and the manner of application and use of such adapters are clearly illustrated in Figures 2 to 5. Referring to these figures, each of the adapters as shown, comprises a tongue engaging portion or section preferably in the form of a short flat socket portion 7 and a relatively long and preferably flat flexible or bendable tongue portion 8 connected to one end of said socket portion; this tongue portion 8 when the adapter is of the form in which it is designed to be used, extending from the point of connection thereof with the socket portion 7 at an angle, preferably substantially a right angle, to said socket portion. The tongue engaging or socket portion and tongue portion of each such adapter are preferably integrally formed from a single thin piece of suitable metal. The socket of the portion 7 of each such adapter is preferably of such dimensions as to receive one of the tongues 2 of the fastener for which it is designed with the opposite side walls of the socket in frictional engagement with said tongue; and the flat tongue portion 8 of the adapter is preferably of the same width and thickness as each of the fastener tongues and may be of the same length as or longer or shorter than the latter. The tongue portions of the adapters herein disclosed are somewhat shorter than the fastener tongues.

When a file fastener has been filled to its normal capacity with the papers of a file, as shown in Figure 1, and it is desired to increase the capacity thereof so that more sheets may be added to the file, the end portion 2' of each of the tongues is bent upwardly from its horizontal holding position until it is in alignment with the main portion of the tongue. The keeper 3, if used, is now removed from its engagement with the tongues 2, and an adapter such as above described, is then applied to the end portion 2' of each of said tongues by moving the socket portion 7 of the adapter, while said socket portion is maintained in a vertical position with the end thereof from which the tongue portion 8 extends directed towards the file sheets 6, downwardly over such end portion until the said tongue portion 8 is brought to that horizontal position in which it engages the uppermost file sheet. The adapters may each be thus applied with its tongue portion 8 extending either outwardly from the respective tongue 2 (as in the case of the adapter shown at the right side of Figure 2) or in the opposite direction, that is, inwardly from the said tongue. After such application of an adapter to one of the tongues 2 of the clamping member, the socket portion 7 thereof is grasped and moved angularly (as indicated, for example, by the arrow A in Figure 2) down against the uppermost of the sheets 6. In this operation the end portion 2' of the tongue 2 to which the adapter is applied is, of course, bent back to a horizontal position adjacent the top sheet 6, and the tongue portion 8 of the adapter is brought to a vertical position in alignment with the main vertical portion of the said tongue 2.

When adapters such as described have been thus applied to both tongues of the fastener clamping member and angularly positioned as described, the result is a modified fastener device of much greater capacity than the original fastener, this being due, of course, to the increased effective length of the tongues. As shown in Figure 3, there may now be added to the original

file sheets 6 any desired number of sheets 6' within the capacity of the extensions to the tongues 2 provided by the tongue portions 8 of the adapters. The sheets 6' are perforated as indicated at 4', in the same manner as the sheets 6. The added sheets are secured in place either by bending the upper projecting end portions 8' of the adapter tongues down directly against the uppermost of said sheets, or by positioning the keeper 3 on top of the sheets with the spaced openings 5 of the keeper engaged by the said end portions 8' and then bending the latter down against the keeper.

If it is desired to increase the capacity of the modified fastener device shown in Figure 3, this may be accomplished merely by applying another adapter of the type herein described, to the portion 8' of each of the adapters already incorporated in such modified fastener. Still further increases in the capacity of such fastening device may be effected in a similar manner.

What I claim is:

1. The combination with a file fastener clamping member comprising a base section, and tongues having portions extending angularly from the base section in spaced relation through sheets to be secured together and end portions bent down over said sheets, of a pair of separate and independent extension devices for said tongues respectively, each of said devices comprising an engaging portion applied to the bent end portion of one of said tongues and a portion extending from said engaging portion substantially in the same plane as and in alignment with the angularly extending portion of the said one of said tongues.

2. The combination with a file fastener clamping member comprising a pair of spaced flat tongues having sheet engageable portions extending in substantially parallel relation through sheets to be secured together and bent end portions overlying said sheets; of a pair of separate and independent extension devices for said tongues respectively, each of said devices comprising an engaging portion removably applied to the bent end portion of one of said tongues and a flat tongue portion extending from said engaging portion at an angle thereto and substantially in the same plane as and in alignment with the sheet engageable portion of the said one of said tongues.

3. The combination with a file fastener clamping member comprising a pair of tongues having spaced sheet engageable portions extending in substantially parallel relation through sheets to be secured together and end portions bent angularly with respect to said engageable portions and overlying said sheets, of a pair of extension devices for said tongues respectively, each of said devices comprising a socket portion engaged by the bent end portion of one of said tongues and a tongue portion extending angularly from said socket portion and substantially in alignment with the sheet engageable portion of the said one of said tongues.

4. The combination with a file fastener clamping member comprising a tongue having a sheet engageable portion extending through sheets to be secured together and an end portion bent angularly with respect to said engageable portion and overlying said sheets, of an extension device for said tongue comprising an engaging portion removably and frictionally secured to the bent end portion of said tongue and a tongue portion extending angularly from said engaging portion.

tion and substantially in the same plane as and in alignment with the sheet engageable portion of said tongue.

5. The combination with a file fastener clamping member comprising a tongue having a sheet engageable portion extending through sheets to be secured together and an end portion bent angularly with respect to said engageable portion and overlying said sheets, of an extension 10 device for said tongue comprising a socket portion engaging over the bent end portion of said tongue and a tongue portion extending angularly from said socket portion and substantially in alignment with the sheet engageable portion of 15 said tongue.

6. An extension device for a tongue of a file fastener clamping member, comprising a portion telescopically engageable with the end portion of 20 said tongue and a bendable tongue portion con-

nected with said engageable portion and extending from its point of connection therewith substantially at a right angle thereto.

7. An integral extension member for a tongue of a file fastener clamping member, comprising 5 a flat socket portion engageable over the end portion of said tongue and a flat bendable tongue portion connected to one end of said socket portion and extending from said end substantially at a right angle to the socket portion. 10

8. A file fastener adapter or extension device comprising a flat bendable tongue section adapted to be inserted through superimposed sheets to be secured together, and a socket section connected to said tongue section and extending from 15 its point of connection therewith substantially at a right angle thereto said socket section being adapted to receive and frictionally engage the end portion of a tongue similar to said tongue section. 15
